UNITED STATES PATENT OFFICE

170,400

RAILWAY CAR BODY

James E. Candlin, Jr., Hammond, Ind., assignor
to Pullman-Standard Car Manufacturing Com-
pany, Chicago, Ill., a corporation of Delaware

Application May 4, 1951, Serial No. 15,068

Term of patent 14 years

(Cl. D66—1)

To all whom it may concern:

Be it known that I, James E. Candlin, Jr., citizen of the United States of America, and resident of Hammond, Indiana, have invented a new, original, and ornamental Design for a Railway Car Body, of which the following is a specification, reference being had to the accompanying drawings, forming part thereof.

In the drawings:

Fig. 1 is a general perspective view of a conventional railway car body in which my new design is incorporated, having portions broken away better to reveal the disposition of the bedrooms within the vehicle and showing the supporting trucks in dotted lines;

Fig. 2 is a general perspective view of the bedrooms in the railway car body and having portions broken away to afford a better illustration of the interior;

Fig. 3 is a horizontal mid-sectional view taken through the bedrooms showing one room made up for sleeping and one for daytime use;

Fig. 4 is a horizontal mid-sectional view taken through the bedrooms showing them ensuite for daytime use;

Fig. 5 is a vertical longitudinal sectional view through the bedrooms, taken on the line 5—5 of Fig. 3;

Fig. 6 is a vertical longitudinal sectional view through the bedrooms, taken on the line 6—6 of Fig. 4;

Fig. 7 is a vertical transverse sectional view through a bedroom, taken on the line 7—7 of Fig. 3; and

Fig. 8 is a vertical transverse sectional view through a bedroom, taken on the line 8—8 of Fig. 4.

The characteristic features of the present design reside in the bedroom interior design shown in the drawings.

I claim:

The ornamental design for a railway car body, substantially as shown and described.

JAMES E. CANDLIN, JR.
